UNITED STATES PATENT OFFICE.

ULYSSES GRANT MCQUEEN, OF NEW YORK, N. Y.

CASEMENT-ADJUSTER.

1,211,733.

Specification of Letters Patent. Patented Jan. 9, 1917.

Application filed March 30, 1915. Serial No. 18,163.

To all whom it may concern:

Be it known that I, ULYSSES GRANT MCQUEEN, a citizen of the United States, residing at New York, in the county of New York and State of New York, have invented certain new and useful Improvements in Casement-Adjusters, of which the following is a specification.

This invention relates to casement adjusters.

The adjuster herein referred to is particularly designed for use in connection with that type of casement which is free for vertical sliding adjustment and also for horizontal swinging movement. It is, therefore, deemed advisable to mention and to properly emphasize that among other objects in view, the principal points of advantage in the structure lie in its adaptability to casements of the kind mentioned and to also invite attention to such features of the structure which satisfactorily contribute with one another to minimize friction between the working parts of the structure at the time of the initial opening of the casement or the closing thereof; and, further, the provision of means which will properly accommodate the vertical movement of the casement and at the same time hold the casement at any desired point in its horizontal adjustment.

Another object of the invention is the provision of a casement adjuster, which, on a predetermined movement of the casement in a horizontal direction, the casement may be frictionally held in its adjusted position, but in such manner that will permit of its further manual adjustment in a horizontal direction without the necessity of manually actuating the adjuster itself.

Aside from the extreme simplicity and practicability of the structure, it is also desired that notice be given the manner in which the friction between the sliding parts of the adjuster can be regulated to suit ordinary wear and tear of the parts and to also prevent the casement from being accidentally moved from its intended point of adjustment.

In the accompanying drawings:—Figure 1 is an elevation of a window structure, showing in dotted lines the position of the adjuster on vertical movement of the casement and the normal position of the casement adjuster in full lines. Fig. 2 is a vertical section through the same, showing the

casement in a partly opened position. Fig. 3 is a perspective view of the adjuster. Fig. 4 is a longitudinal section therethrough. Fig. 5 is a transverse section 60 therethrough. Fig. 6 is a longitudinal section through both members of the adjuster and illustrating the means for limiting the sliding movement in one direction of one of the members within the other. 65

The adjuster, as stated, is particularly designed for use in connection with casements which are free to slide vertically and to also swing horizontally. The casement shown in the accompanying drawings and illustrated at C is of the inwardly opening type. However, it is understood that it may be just as effectually used in connection with a casement which is to swing in an outward horizontal direction if such be advisable. 75

The adjuster consists of two mating members 1 and 2, the former being in the nature of a tube and the latter in the form of a rod, which is free to slide in a longitudinal direction within the tube and also free 80 to rotate therein. The tube is closed at one end by a cap 3 which has an integral stud 4 rising in a vertical direction therefrom and passing through a double frusto-conical passage 5 formed in an attaching plate 85 or bracket 6 which may be screwed or otherwise suitably secured to the frame at the top thereof at a point adjacent to the upper horizontal rail of the casement. The passage 5 has its branches A and B arranged 90 so that the small end of one branch has its walls directly merged into the small end of the walls of the other branch. In this manner it is seen that the stud 4 is permitted to rock or turn in the bracket. At this point, 95 it is stated that this adjustment is preferred, and in fact, necessary, in order that the device will accommodate itself to a corresponding movement of the casement in a vertical direction. Interposed between the 100 cap 3 and the bracket 6 is a spring 7 which serves to prevent undue rattling of the parts.

At the opposite end of the tube is a cap 8 having a shoulder 9 which forms a stop against which the coacting shoulder 10 on 105 the rod 2 is designed to engage so as to limit the outward swinging movement of the rod and, consequently, prevent its entire separation from the tube 1. The rod 2 freely slides through the cap 8 and through the tube 1 110 and, as shown, it is provided at suitable points in its length with circular grooves 11.

The cap 8 has a cylindrical extension 12 in which is threadedly mounted for adjustment a plug 13. Mounted to move axially of the cylinder 12 is a spherical body or latch element 14 against which a spring 15 bears, so as to normally hold such latch element frictionally against the rod 2 and to cause said element to be yieldingly projected into anyone of the grooves 11 on sliding adjustment of the rod 2. The outer end of the spring, of course, bears against the plug 13 and incident to the fact that the latter is threadedly adjustable within the cylinder, it, of course, follows that the spring may be placed under such tension as may be necessary to a proper retention of the respective parts 1 and 2 of the adjuster. The spherical body or latch element 14 when extended into anyone of the grooves 11 serves to hold the rod securely in its adjusted position but it does not hinder such free rotation of the rod as is necessary to accommodate lateral inequalities in the movement thereof.

It is desired that the friction between the latch member and the sliding rod be varied at certain times in the movement of the casement so as to permit the latter to be initially moved to its open position or to its full closed position, and to accomplish this purpose, the rod is of reduced diameter through a section of its length such as illustrated at 16. It is seen that when the mentioned reduced portion of the rod is within the tube and disposed at right angles to the axis of the cylinder 12, the ball latch element 14 will bear thereagainst and as the spring is not compressed to the extent that it is when engaged in one of the grooves 11, it is evident that the two parts, namely, the tube 1 and the rod 2 may move with more relative freedom and the casement may then be properly adjusted with relation to the frame without any strenuous or laborious effort of the operator.

The extremity of the reduced end 16 of the rod 2 is provided with a passage 17 which is somewhat similar to the passage 5 formed in the bracket 6. Through this passage and through the ears of the bracket 18 is passed a screw 19. The bracket 18 is adapted to be screwed or otherwise suitably secured to the casement and as a result of the just-described manner of connecting the bracket to the rod, the rod is free to rock slightly from the bracket. The bracket 18 is, of course, disposed at right angles to the bracket 6 and by connecting the tube 1 and the rod 2, respectively, with both of the brackets referred to, the casement is most satisfactorily accommodated not only in its described movements but in any other irregular movements thereof as may result from

constant operation of a structure of this nature.

I claim:

1. A holding device for vertically movable and horizontally swinging casements, comprising a bracket adapted to be secured to the frame, a tube mounted to tilt vertically and swing horizontally from said bracket, a rod sliding in said tube and free to oscillate therein and provided with spaced annular grooves and a yieldingly mounted spherical locking body carried by said tube and adapted to be successively projected into said grooves as the rod is adjusted longitudinally therein.

2. A holding device for vertically movable and horizontally swinging casements, comprising, a bracket adapted to be secured to the frame, a tube mounted to tilt vertically and swing horizontally from said bracket, a rod sliding in said tube and free to oscillate therein and provided with spaced annular grooves and a yieldingly mounted spherical locking body carried by said tube and adapted to be successively projected into said grooves as the rod is adjusted longitudinally therein, the said rod having a transversely restricted portion adapted to freely pass over said locking body initially on movement of the rod from the tube and on the normal projection of the rod in the tube.

3. A holding device for vertically movable and horizontally swinging casements, comprising, a tube mounted to swing vertically and horizontally and to tilt vertically from the casement, said rod being movable in the tube, a stop on the rod, a stop on the tube adapted to co-act with the first stop to limit the projection of the rod from the tube, and a securing device carried by the tube and co-acting with the rod to hold the same against movement in the tube.

4. A holding device for vertically movable and horizontally swinging casements, comprising, a tube adapted to swing horizontally and to tilt vertically from the frame, a rod adapted to be mounted to swing horizontally and to tilt vertically from the casement and with the tube and mounted to slide in said tube, a member having a stop, said member being secured to the tube, a stop formed on the rod and adapted to co-act with the first stop, and a locking device carried by said member and adapted to co-act with the rod to hold the latter adjusted in the tube.

In testimony whereof I affix my signature in presence of two witnesses.

ULYSSES GRANT McQUEEN.
